(57) **CLAIM**

The ornamental design for an injection syringe, as shown and described.

DESCRIPTION

FIG. 1 is a front elevational view of an injection syringe showing my new design;

FIG. 2 is a rear elevational view thereof;

FIG. 3 is a left side elevational view thereof, a right side elevational view being a mirror image;

FIG. 4 is a top plan view thereof;

FIG. 5 is a bottom plan view thereof;

FIG. 6 is a perspective view thereof; and,

FIG. 7 is a perspective view thereof shown in a using state. In the drawings the broken lines represent portions of the injection syringe which form no part of the claimed design.
